UNITED STATES PATENT OFFICE.

JOHN OTTO ALMEN, OF SEATTLE, WASHINGTON.

INTERNAL-COMBUSTION ENGINE.

Application filed May 21, 1923. Serial No. 640,388.

This invention relates to improvements in internal combustion engines and more particularly to piston connections for use in engines of that type wherein a plurality of 5 pistons are arranged circularly about and are adapted to reciprocate in lines parallel with a centrally located power shaft, and wherein power is transmitted to the shaft through the intermediary of a rocker that is rotatably 10 mounted on an inclined journal on the shaft and which has movable bearing connections with the several pistons.

It is the principal object of the invention to provide an improved form of connection 15 whereby difficulties in lubrication that have heretofore been encountered are avoided and a better construction produced. Also, to provide connecting bearings, the parts of which are easily assembled, which permit all 20 of the necessary rotative movements required in the construction, which are durable, efficient and through which certain turning motion will be imparted to the pistons whereby better lubrication is provided and scoring is 25 prevented.

Other objects of the invention reside in the various details of construction and combination of parts embodied in the invention, whereby the motion of the rocker is confined 30 to its natural path of travel.

In accomplishing these and other objects of the invention, I have provided the improved details of construction, the preferred forms of which are illustrated in the accompanying 35 drawings, wherein—

Figure 1 is a central, longitudinal section of an engine equipped with bearing connections constructed and assembled in accordance with present invention.

Figure 2 is a longitudinal, sectional view of one of the engine pistons, showing its connection with an arm of the rocker and illustrating the relative position of the parts when the piston is at one extreme of its 45 travel.

Figure 3 is a transverse sectional view of the same, taken on the line 3—3 of Figure 2.

Figure 4 is a top view of the piston and wrist pin carrier, as shown in Figure 2.

Figure 5 is an enlarged view of a part of the rocker and one of its connecting arms.

Figure 6 is an enlarged, upper-end view of a wrist pin carrier, illustrating, in dotted lines, the path of travel of the studs fixed in 55 the rocker arm, and the formation of the

bearing surfaces on the carrier, against which the studs operate.

Referring more in detail to the drawing, 1 designates the engine casing wherein there is provided a plurality of cylinders 2 arranged in alinement in opposite ends of the casing, and wherein pistons 3 are reciprocally contained. The cylinders are disposed circularly about and in parallel relation with a centrally located power shaft 4, this being 65 supported adjacent its ends within anti-friction bearings 5 which retain it functionally in position.

Formed on the drive shaft between the inner ends of the alined cylinders is a journal 6, the axial line of which bisects the axial line of the shaft 4 at an acute angle, and mounted revolvably on this journal, upon anti-friction bearings 7 is a rocker 8 through 70 which power is transmitted from the pistons to the shaft. The rocker is of ring-like construction and is provided with a plurality of radially extending arms 10 each of which is pivotally connected at its end by means of a wrist pin 11 with a cylindrical wrist pin 75 carrier 12 that is slidably mounted within a bore 13 in the yoke joining alined pistons 3; each of the carriers being mounted to move rotatably and reciprocally within its bore 80 which is formed centrally between the pistons and in a line that is perpendicular to the axis of their cylinders.

By reason of mounting the rocker on an inclined journal, reciprocation of the power driven pistons in proper sequence will impart a wabbling motion to the rocker which in turn imparts a rotating motion to the shaft 4, and it is due to this manner of connecting the pistons with the rocker that it is required there be no fixed relation between 90 the bearing members and the piston or the rocker, and that the wrist pin carriers be permitted, as the pistons reciprocate, to move radially toward and from the shaft 4 and also that they be permitted to move rotatably 95 within the pistons; both of these movements being provided for.

By reason of the manner in which the carriers are mounted it is apparent that, as the shaft rotates, the rocker will be given a certain wabbling motion which not only imparts rotative movement to the shaft but also, due to the character of the connection, imparts a certain rotative movement in opposite directions to the pistons. This move- 100

ment is illustrated in Figure 4 by means of the dotted line as shown at 15, which is the course that would be inscribed by a point on a piston as it moves reciprocally within its cylinder. This movement is very much desired since it provides better and more even lubrication.

Also, due to the arcuate movement of the rocker arms and the wobbling motion of the rocker as the shaft rotates, it is apparent that this figure 8 motion will be imparted to each of the wrist pin carriers as they move reciprocally within the piston bores. This movement likewise facilitates lubrication and prevents, to a certain extent, wear on the parts.

In order that the motion of the rocker will be confined to its natural path of travel and to prevent its rotation in a direction opposite to the direction of the crank shaft, also for the purpose of eliminating noise that is incidental to operation of the engine, I have fixed bearing studs 20 on the outer ends of each of the rocker arms 10, as is best illustrated in Figures 3 and 5. These studs are adapted to slidably engage with bearing guide surfaces 21 and 22 formed in spaced relation in the upper end portions of the wrist pin carriers. These studs, due to the arcuate and rocking motion of the rocker in operation, follow courses of the figure 8 form, as shown in the dotted lines at 26 in Figure 6. Lateral thrust exerted against the pistons by the rocker arms is then received by the bearing surfaces 21 and 22 which are so shaped as to conform to the resulting movement of the studs which engage them during reciprocation of the pistons. In this way the motion of the rocker is confined to a path any point on the rocker would follow naturally, provided there are no external forces acting upon the rocker such as torque of the engine, friction or gas pressure.

While I have shown each rocker arm equipped with two bearing studs, this is not absolutely essential since the same result could be had by the use of a single stud in each arm and by bringing the guide bearing surfaces closer together. It is also apparent that the same result can be had by locating the studs at opposite sides of the rocker arms beneath the bearing connection, as is illustrated in dotted line at 26 in Figure 5, and by inverting the carrier 12 so that the guide bearing surfaces will lie in the same relation to these studs as they do in the illustrated construction.

It has been found also that unbalanced forces that would tend to, or which will cause rotation of the wobbler in engines of different horse power than that for which the present has been designed, can be over-

come by forming the bearing portions of arms 10 through which pins 11 extend at an obtuse angle with respect to the radial line of the arm. This angular relation can be made such that it will throw the parts in such balance when in operation that those forces which otherwise would tend to cause rotation of the wobbler will be neutralized. In this construction the axial line of pins 11 would be inclined in the direction of the dotted line through the bearing shown in Figure 5.

Having thus described my invention, what I claim as new therein and desire to secure by Letters Patent, is:

1. In an engine of the class described, a power shaft having an inclined journal, a rocker rotatable in the journal having a radially extended rocker arm and a piston mounted to reciprocate parallel with the shaft and having a yoke with a transverse bore therein of a cylindrical wrist pin carrier slidably and rotatably contained in said bore and provided within opposite faces with bearing surfaces, a wrist pin fixed in said carrier and pivotally connecting the same with the rocker arm, and studs fixed in said arm for slidable engagement with said bearing surfaces.

2. In an engine of the class described, a shaft having an inclined journal, a piston mounted to reciprocate parallel with the shaft and having a yoke provided with a transverse bore, a rocker rotatable on the journal and having an arm extended therefrom, a bearing fitted slidably and rotatably in the piston and pivotally attached to the rocker arm and having guide surfaces therein and means on the arm adapted to engage the said guide surfaces whereby the movement of the rocker is confined to and guided in its natural path.

3. In an engine of the class described, a power shaft having an inclined journal, a rocker rotatable on the journal having a radially extending arm, a stud fixed at the end of said arm, a pair of aligned pistons with a connecting yoke mounted to move reciprocally parallel with the shaft, said yoke having a transverse bore therein, a wrist pin carrier mounted for rotary and slidable movement within the bore, and a wrist pin fixed in said carrier and pivotally connecting the same with the rocker arm, said carrier having bearing surfaces formed therein to be engaged by the said stud during operation of the engine and so shaped as to confine the movement of the rocker to its natural path.

Signed at Dayton, Ohio, this 30th day of January, 1923.

JOHN OTTO ALMEN.
